LOADING PAN

Patrick F. Toohey, Burgettstown, Pa., assignor of one-half to Mike Robb, Slovan, Pa.; Catherine Toohey administratrix of said Patrick F. Toohey, deceased

Application May 23, 1945, Serial No. 595,326

2 Claims. (Cl. 198—220)

1

The present invention relates to a new and useful improvement in reciprocating loading pans of a type used in shaker conveyor lines in the mining of coal and positioned between the usual duck bill into which the coal is initially loaded and the conveyor chain for transporting coal to mine cars, such loading pans serving to convey the coal from the duck bill to the conveyor chain and the invention has for its primary object to provide a discharge opening in the side of the pan together with a transversely curved baffle or partition adjacent the opening and by means of which waste products may be discharged from the pan before reaching the conveyor.

In the mining of coal it is frequently necessary to separate and remove a large quantity of waste, such as slate, from the working face of the mine and it is the usual practice to load this waste material or slate onto mine cars, in the same manner that the coal is loaded, which means that such slate passes through the loading pan on its way from the duck bill to the conveyor chain.

Such handling of the waste material incurs considerable expense and it is accordingly an object of the present invention to provide means for conveying the waste material to an unused part of the mine and discharging the material at that point and thus eliminate the labor and expense usually required for transporting the waste material entirely out of the mine and away from the mine entrance in cars or the like.

A further object of the invention is to provide an attachment for such loading pans which may be easily and quickly removed therefrom when not in use so that the loading pan may be used in the usual manner in conveying the waste material from the mine working as well as the coal and loading the same into the mine cars.

A further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary top plan view of a loading pan showing the waste removal attachment in position thereon.

Figure 2 is a side elevational view.

2

Figure 3 is a longitudinal sectional view taken substantially on a line 3—3 of Figure 1.

Figure 4 is a transverse sectional view taken substantially on a line 4—4 of Figure 1.

Figure 5 is a transverse sectional view taken substantially on a line 5—5 of Figure 2, and

Figure 6 is a perspective view of a transversely curved waste removal partition or baffle for the loading pans.

Referring now to the drawings in detail wherein for the purpose of illustration I have disclosed a preferred embodiment of the invention. The numeral 5 designates a reciprocating loading pan of conventional construction and of a type forming part of the conventional shaker conveyor line equipment of a coal mine, the pan including outwardly projecting flanges 6 at the upper edges thereof. Since such shaker conveyor lines are well understood in the art, conventional illustration of the reciprocating loading pan is deemed sufficient for the present purposes.

At longitudinally spaced intervals the side walls of the pan are formed with one or more openings 7 in the opposite sides of the pan, the openings 25 being normally closed by a door 8 hinged at one edge to the bottom of the pan by means of hinge members 9 and the free edges of the doors are formed with apertured lugs 10 adapted for aligning with similar lugs 11 on the upper edges of the 30 flanges 6 adjacent the sides of the openings 7.

Locking pins 12 are removably inserted in the aligned openings of the lugs 10 and 11 to secure the door in its closed position.

When the doors 8 are secured in their raised or closed positions the pan 5 is used in the usual manner for conveying coal from the loading duck bill to the loading conveyor forming part of the usual loading equipment of the mine and neither of which it has been deemed necessary to illustrate.

When it is desired to remove waste material, such as slate or the like, from the mine working, without loading such waste material onto the mine cars, one of the doors 8 is opened and a 45 transversely curved baffle or partition 13 is placed in the pan with one end bent longitudinally to form a flange 14 extending outwardly at the outside of the pan at the rear edge of the opening 7, as shown in Figure 1 of the drawings, and the other end of the partition or baffle 13 has its upper edge bent downwardly to form a channel-shaped flange 15 adapted for engaging the flange 6 at the opposite side of the pan.

A screw or pin 16 is threaded through the 50 flange 15 and through an aligned opening in the

flange 6 for securing the adjacent end of the baffle or partition 13 against movement in the pan when subjected to the force or pressure of the material travelling along the pan in the direction shown by the arrows in Figure 1 of the drawings and striking the partition to deflect the material outwardly through the opening 7 in the side of the pan.

A chain 11 connects the pin or screw 16 to the partition 13 to prevent loss thereof. The baffle or partition 13 is curved forwardly from the rear edge of the opening 7 to guide the material toward the opening in the side of the pan for discharge therefrom onto the floor of an unused part of the mine.

It will be apparent that either or both sides of the pan 5 may be provided with one of the openings 7 and doors 8 and the baffle or partition 13 is interchangeably positioned at the rear edge of either opening to discharge the waste material from either side of the pan.

In view of the foregoing description taken in conjunction with the accompanying drawings it is believed that a clear understanding of the construction, operation and advantages of the device will be quite apparent to those skilled in the art. A more detailed description is accordingly deemed unnecessary. It is to be understood, however, that even though there is herein shown and described a preferred embodiment of

the invention the same is susceptible to certain changes fully comprehended by the spirit of the invention as herein described and the scope of the appended claims.

5 I claim:

1. A loading pan of the class described having an opening in a side thereof, a door adapted for closing the opening, a baffle extending transversely in the pan and curved in a forward direction, a flange at one end of the baffle adapted for engaging the outer side of the pan at the rear edge of the opening to prevent longitudinal and lateral movement of the baffle in one direction, and means at the other end of the baffle for attaching to the pan to prevent longitudinal and lateral movement of the baffle in an opposite direction.

2. A loading pan of the class described having an opening in a side thereof, a door adapted for closing the opening, a baffle extending transversely in the pan and curved in a forward direction, a flange at one end of the baffle adapted for engaging the outer side of the pan at the rear edge of the opening, said pan having outwardly projecting flanges at its upper edge, and a channel-shaped flange on the upper edge of the baffle at its other end and adapted for engaging the flange at one side of the pan.

PATRICK F. TOOHEY.
